UNITED STATES PATENT OFFICE.

BENJAMIN CRABTREE CALDERWOOD, OF VALLEY FALLS, RHODE ISLAND, ASSIGNOR TO PRICE-CAMPBELL COTTON PICKER CORPORATION, OF NEW YORK, N. Y., A CORPORATION OF DELAWARE.

LUBRICATING DEVICE.

1,174,386.

Specification of Letters Patent.

Patented Mar. 7, 1916.

Application filed April 30, 1913. Serial No. 764,518.

To all whom it may concern:

Be it known that I, BENJAMIN CRABTREE CALDERWOOD, a citizen of the United States, residing at Valley Falls, in the county of Providence and State of Rhode Island, have invented certain new and useful Improvements in Lubricating Devices, of which the following is a specification.

My invention relates to improvements in oiling systems for carriers in cotton-picking machines whereby the lubricant is led, under the action of gravity, from a sight feed oil cup to an iron tube having a bottom or outlet end covered over with a piece of cotton wicking, herein described and hereafter referred to as an oil retainer. The oil is conveyed to the carriers by the action of oil gatherers, which consist of short pieces of tubing with holes drilled in the shell, and forced into the extreme upper end of the spiral shafts in the carriers, passing in succession under the retainer as the carriers revolve around the drum center, each gatherer wiping off a quantity of oil, which finds its way to the interior of the carriers through the holes provided.

The objects of my invention are: first, to insure constant, plentiful and equal lubrication to each and every carrier in the cotton-picking machine; and second, to provide means for sufficiently lubricating the various inclosed parts in the carriers, as well as the sliding clutch and combined pinion and clutch at the upper end of the spiral shafts.

I attain these objects in the manner illustrated in the accompanying drawings, in which—

Figure 1 is a section through the top drum plate and covers, the oil retainer, carriers, and upper and lower carrier wheels, and illustrates the path of the lubricant from the time of leaving the sight feed oil cups until it leaves the carrier. Figs. 2, 3 and 4 show details.

Referring to the drawings, 1 is the sight feed oil cup, 2 the duct which leads the lubricant from the reservoir to an oil retainer 3, 4 the wick, which absorbs the lubricant, and 5 the tubular, wiping oil gatherer at the extreme upper end of the spiral shaft in the carrier.

6 is the spiral gear-shaft, the greater por-

tion of which is inclosed in and rotates in the carrier, 7 the spiral gear, integral with 55 the shaft 6, and 8 the carriers.

9 are the combined pinions and finger sockets, meshing with the spiral gears 7, and which, in rotating, force the lubricant into their respective bearings, and 10 the 60 bottom carrier pivots, which serve the double function of acting as a step for the spiral shaft 6, and a pivot for the carriers.

11 is a fixed circular gear ring, around which revolve the carriers and their 65 respective mechanisms, 12 the clutch tension springs, and 13 the clutches, which also derive their lubricant from the oil retainer 2, via the oil gatherers 5.

14 are the cam arms, 15 the top carrier 70 wheel, 16 a picking finger, 17 the main translating cam, 18 the top drum plate, which supports the entire drum mechanism, and 19 and 20 are gear covers over the top drum plate.

75 21 is the lower carrier wheel, 22 a hardened steel stop ring upon which rest the carriers 8. 23 are the dowels which secure the pivot studs 10 to the carriers 8; 24 the screws which hold the drum centers to the 80 top drum plate; 25 a lock nut for the oil retainer 3; and 26 a hole drilled through the pivot stud 10 for the purpose of allowing the excess lubricant to escape.

The oil gatherer 5 is a tube fixed project- 85 ingly in the upper end of the hollow shaft 6. This tube where it projects from the shaft has its wall perforated at 5^a. The upper end of the hollow shaft is provided at X with an annular oil gathering groove 90 shown formed by an inward bevel of the upper end wall of the sleeve member of the upper retainer 12^a for the spring 12. The groove X catches and diverts oil dripping from the wick into the tubular wiper 5 whence 95 it runs downwardly through the chamber of the hollow shaft 6. The upper open end of the wiper or gatherer 5^a contacts gently with the under end of the wick and during rotation of the shaft 6 and the wiper, the latter gathers oil from the wick which can be adjusted endwise by the lock-nut 25. In cotton picking machines it is of great importance to so control the lubricant that none of it will get on the picker fingers and 100 so grease the cotton being gathered.

What I claim is:—

In a cotton picker the combination of an oil wick with a hollow carrier shaft provided with an open ended tubular oil-gatherer operating adjacent the wick end, the tubular oil-gatherer having an exposed perforated side wall below its end opposed to the wick; and an annularly grooved means opposed to the wick and surrounding the 10 perforated wall, whereby oil coming from

the wick exteriorly of the oil gatherer is guided into the chamber of the oil gatherer.

In testimony whereof I have hereunto set my hand in the presence of two subscribing witnesses, this 25th day of April, 1913.

BENJAMIN CRABTREE CALDERWOOD.
